ATTORNEY.

UNITED STATES PATENT OFFICE.

GILBRETH BROWN, OF PROVIDENCE, RHODE ISLAND, ASSIGNOR TO THE E. A. POTTER CO., OF PROVIDENCE, RHODE ISLAND, A CORPORATION OF RHODE ISLAND.

DESIGN FOR A WATCHCASE-PROTECTOR.

51,298.

Specification for Design.

Patented Sept. 25, 1917.

Application filed July 30, 1917. Serial No. 183,632. Term of patent 3½ years.

To all whom it may concern:

Be it known that I, GILBRETH BROWN, a citizen of the United States, residing at the city of Providence, county of Providence, State of Rhode Island, have invented a new, original, and ornamental Design for a Watchcase-Protector, of which the following is a specification, reference being had to the accompanying drawing, forming part thereof.

I claim:

The ornamental design for a watch case protector as shown.

GILBRETH BROWN.
